[57] CLAIM

The ornamental design for a club chair, substantially as shown and described.

DESCRIPTION

FIG. 1 is a front perspective of a club chair embodying my novel design;

FIG. 2 is a rear perspective thereof;

FIG. 3 is a left-side perspective thereof;

FIG. 4 is a top perspective thereof; and

FIG. 5 is a bottom perspective of my novel design.
The appearance of the side of the club chair not shown in the drawing is identical with the appearance of the side shown in FIG. 3.

FIG. 1

FIG. 3

FIG. 4

FIG. 5
